UNITED STATES PATENT OFFICE.

GEORGE WESTON CRAIG, OF PROVO CITY, UTAH.

RAILROAD-TICKET.

SPECIFICATION forming part of Letters Patent No. 660,417, dated October 23, 1900.

Application filed October 26, 1899. Serial No. 734,792. (No model.)

To all whom it may concern:

Be it known that I, GEORGE WESTON CRAIG, of Provo City, in the county of Utah and State of Utah, have invented new and useful Improvements in Railroad-Tickets, of which the following is a full, clear, and exact description.

My invention relates to railroad-tickets, and particularly to those known as "coupon-tickets" and issued for journeys extending over the lines of several companies.

One object of my invention is to provide a ticket form which will be available for passage between any two of a number of stations and which will enable the issuing agent to make the ticket read via any one of the several lines which may be traveled over to reach the final destination. Thus according to my invention one form of ticket will suffice where hitherto a very large number of forms has been required, thus effecting a considerable saving and affording greater convenience, since the stock of tickets may be materially reduced.

Another object of my invention is to so arrange the parts of the ticket that all of them may be readily punched together and that fraud will be guarded against.

Reference is to be had to the accompanying drawings, forming a part of this specification, in which similar characters of reference indicate corresponding parts in all the figures.

Figures 1^a and 1^b show the improved ticket open or extended, Fig. 1^b being the right-hand continuation of Fig. 1^a. Fig. 2 is a broken plan showing the ticket as it appears when folded, and Fig. 3 is a sectional elevation on the line 3-3 of Fig. 2.

The ticket shown in the drawings is a three-coupon ticket—that is, one coupon will be good for passage from the starting-station to a junction-point, the second coupon from this junction-point to another junction-point, and the third to the final destination. The principles of construction described herein-after may, however, be applied to any ticket having two or more coupons or sections.

The ticket shown comprises the following parts: a "general-information" section A, three passenger-coupons B C D, and an agent's stub E. The ticket is adapted to be folded along the lines *a a*, which separate the

sections from each other, and, if desired, folding may be facilitated by scoring or perforating the ticket along said lines. Such means would also facilitate the successive tearing off of the ticket-sections.

The general-information section A (see Fig. 1^a) has a blank space for the insertion of any remarks or matter the company may desire to add—such as a description of the purchaser, or his signature, or other means of identification. At the margin of this section appear the usual indications of the time-limit by year in space A¹, month in space A², and day in space A³. At the bottom is an "index to junction-points" A⁴, having blank spaces, as at A⁵, to be filled in by writing or in any other manner by the agent issuing the ticket. When these blanks have been filled, as shown, the "index" will designate not only the terminal stations of each coupon, but the line available for each of the coupons. Thus in the example shown the ticket is issued for passage from Provo City to Chicago, the first coupon entitling the holder to passage from Provo City to Ogden via the Oregon Short Line, the second coupon reads "From Ogden to Council Bluffs via the Union Pacific," and the third entitles the passenger to transportation on the Chicago and North Western from Council Bluffs to Chicago. As all this appears on the index A⁴, which remains connected with the ticket until the end of the journey, the perpetration of fraud by changing the coupons is practically made impossible.

The passenger-coupons B C D and the agent's stub E are practically alike, differing from each other by details in the heading in the space at the top. Thus coupon B is "Good only from junction-point via line No. 3 and to final destination," while the wording is appropriately changed for the other coupons and for the agent's stub. Another difference between these coupons and the stub will be pointed out hereinafter; but I shall first describe those features in which they are alike. Each of the said parts has at F a list of lines which may be available, with blank spaces F' to receive indications in writing or preferably by numbered punches as to the particular lines selected by the passenger and the order in which they are to be used. Further, in a

section G under the heading "Class" are proper indications and blank spaces to specify the conditions to which the ticket is subject; also, if desired, a blank space for the reception of a baggage-punch mark. At the bottom (or at any other convenient place) is a series of spaces H for the punch-marks of the several conductors. The body of each of the passage-coupons and of the stub comprises four sections or lists, (or generically speaking, one in excess of the number of passage-coupons the ticket contains,) of which the first, I, contains a list of starting-stations and first junction-points, preferably with one or more blanks, so that the name of a less-important station may be written in such blank space. The second section I' contains a list of the various junction-stations at which a traveler coming from one of the starting-stations (in list I) may pass upon a connecting-line, together with further junction-points of such connecting-lines. The third section I² contains a list of the several junction-stations at which a passenger, having traveled over the first-mentioned connecting-line, may be transferred to another connecting-line to reach his final destination, which may be any one of the stations indicated in the list appearing in the section I³. Adjacent to each station-name in the various lists is a space, preferably numbered, as shown, to receive a punch-mark.

While the matter contained in the spaces F G I I' I² I³ is the same for each of the coupons B C D and for the stub E, its arrangement is different in the coupon C and stub E (which are alike in this particular) from the coupons B and D, which again are alike except as to the heading. Sections B and D have the arrangement of sections C and E reversed from left to right, and vice versa—that is, the central columns of station-names are the same; but what is the right-hand column in the sections B and D becomes the left-hand column in the sections C and E, and vice versa. Similarly the spaces F G are at the left in sections B and D and at the right in sections C and E. Also in sections B and D the numerals are at the left of station-names, and in sections C and E they are at the right of such names. The purpose of this arrangement is to bring those spaces of the several sections which are adapted to receive corresponding punch-marks into exact superposition when the ticket is folded, as shown in Fig. 3, so that all of the four parts B, C, D, and E may receive their corresponding punch-marks J at the same time.

The improved ticket is used as follows: Let us assume the passenger desires a ticket from Provo City to Chicago via the Oregon Short Line, (to Ogden,) the Union Pacific, (to Council Bluffs,) and the Chicago and Northwestern. The ticket agent punches the date at A' A² A³ in the usual manner and inserts in the spaces A⁵ of the index A⁴ the indications shown in Fig. 1^a. The agent then folds the ticket along the lines a a, as indicated in full

lines in Fig. 3, and then punches the four sections B C D E, as indicated in Fig. 2—that is, in the line-list F a numerical punch-mark "1" 70 for "O. S. L." (Oregon Short Line,) the mark "2" for "Un. Pac.," and the mark "3" for "C. & N. W." In the station-list I the station "Provo City" is punched. The station "Ogden" is punched both in the list I and in 75 the list I'. The station-name "Council Bluffs" is punched in the lists I' and I² and the final destination, "Chicago," is punched in the last list I³. The nature of the ticket—for instance, "First-class, limited"—is also indicated by 80 a punch-mark in one of the spaces of the section G, if necessary. The agent then tears off his stub E, which he keeps, as usual. The baggage-master will then punch the ticket, if required, and the section A may be folded 85 over the others, so that the ticket will be more handy to carry. The conductors will put their respective punch-marks in the spaces H, and the coupons D, C, and B will be retained by the last conductor of each line, as 90 customary.

It will be seen that the improved ticket will avoid the necessity for a multiplicity of forms and will enable any agent to issue tickets good over a large variety of routes, while the manipulations in punching the ticket are so obvious that mistakes on the part of the issuing agent are not likely to occur. As each of the sections by its punch-marks, or as for the section A by the index A⁴, gives full details as to the stations between which the ticket is good and what lines should be traveled over, the use of the ticket upon other lines connecting the same stations is made impossible, and fraudulent alterations of the 105 ticket are effectively prevented.

It will be obvious that the ticket might be somewhat simplified by the omission of the lateral columns in the lists I and I', in which case the name of each junction-point would have to be punched only once. The addition of the lateral columns, however, is of moment for the auditor's convenience, and I therefore consider said lateral columns not only a useful feature of my ticket, but necessary thereto. 110 115

It is to be understood that I do not limit myself to the exact arrangement of my improved ticket as shown and described, as such arrangement may be varied without departing from the spirit of my invention, and I consider myself entitled to all such variations as come within the scope of my claims.

Having thus described my invention, I claim as new and desire to secure by Letters Patent—

1. A coupon-ticket, comprising a plurality of sections having marks indicating the order in which said sections are to be used, each section also having a list of starting-points, a list of destination-points, a list of intermediate or junction points, and a separate list of the lines available for travel between such starting, junction and destination points, so that, by appropriately punching stations in

said lists, the same form of ticket may be used for travel between any starting-point and any destination-point, over any one of the available lines.

5 2. A coupon-ticket, comprising a plurality of sections having marks indicating the order in which said sections are to be used, each section having a space for the indication of the starting-point, a list of destination-points, 10 a list of intermediate or junction points, and a separate list of the lines available for travel between the starting, junction, and destination points.

3. A coupon-ticket, comprising a plurality 15 of sections having marks indicating the order in which said sections are to be used, each section having a space for the indication of the starting-point, another space for the indication of the destination-point, a list of intermediate or junction points, and a separate 20 list of the lines available for travel between the starting, junction, and destination points.

4. A coupon-ticket, comprising a plurality 25 of sections having marks indicating the order in which said sections are to be used, each section having a space for the indication of the starting-point, another space for the indication of the destination-point, a list of intermediate or junction points, a separate list 30 of the lines available for travel between the starting, junction and destination points, and another section provided with an index hav-

ing blank spaces for the insertion of the names of the terminal stations of each coupon and of the lines for which the ticket is issued.

35

5. A coupon-ticket, comprising a plurality of adjacent sections adapted to be folded one over the other, each section having spaces for the indication of the starting-point and destination-point respectively, a list of intermediate or junction points, and a separate list of the lines available for travel between such starting, junction, and destination points, the relative arrangement of such spaces and lists being reversed, as regards right and left, in 40 adjacent sections so that corresponding spaces of the sections will be in registry or superposition when the ticket is folded, to enable the several sections to be punched simultaneously.

45

6. A coupon-ticket, comprising a plurality of sections each having a list of the lines available for travel, and a list of stations, said lists being entirely independent from each other so that any element of one list may be combined by an appropriate mark with any element of the other list, the list of stations being in a plurality of groups, one of which contains starting-points, another junction-points, and yet another destination-points.
